UNITED STATES PATENT OFFICE.

ANNA ALPLANALB, OF CHICAGO, ILLINOIS.

BUSTLE.

SPECIFICATION forming part of Letters Patent No. 358,914, dated March 8, 1887.

Application filed March 16, 1885. Serial No. 159,043. (No model.)

To all whom it may concern:

Be it known that I, ANNA ALPLANALB, a citizen of the United States, residing at Chicago, in the county of Cook and State of Illinois, have invented certain new and useful Improvements in Bustles, of which the following is a specification, reference being had therein to the accompanying drawings.

My invention relates to bustles for ladies' wear, having for its object the provision of such an article which shall be light, simple, and durable in construction and cheap of manufacture; and the invention consists in making a bustle in sections, the several parts of which are attached together and provided with means for holding them in an extended position when in use, whereby great comfort to the wearer is obtained and a neat and symmetrical appearance is given to the garments, all arranged and combined substantially as hereinafter more fully described, and pointed out in the claims.

In the drawings, Figure 1 is a side elevation of a bustle made in accordance with my invention. Fig. 2 is a top plan view thereof. Fig. 3 is a transverse sectional view on the line xx of Fig. 2. Fig. 4 represents a modified form of my invention. Fig. 5 represents a transverse sectional view on the line yy of Fig. 4.

Referring to the drawings, A B C designate, respectively, the upper, center, or intermediate, and bottom sections of my improved bustle. All the sections have substantially the same construction and configuration, differing only in size. Each section has a web, the several webs being lettered $b c d$, the outer edges of which are cut to conform to the inner surfaces of the cases or sections A B C. Each of the sections is composed of a sheath or casing, E, and a coiled spring, D, the coils of which gradually grow smaller near the ends, as shown, thus imparting to the section to which they conform a crescent shape, the reduced ends of each section being connected to a common band, F, adapted to be secured around the waist of the wearer. The coiled spring of each section is preferably made of one piece of wire, the coils thereof being gradually enlarged from the ends toward the middle until the desired width in cross-section has been attained, when the springs are bent in a semicircle, and

the sheath or casing, having been cut to the corresponding shape, is secured around the spring. The web of each section can, if preferred, be made in one piece with the sheath or casing, or separately and stitched thereto, the inner ends of the web being secured to the waistband F. The intermediate section, B, is made larger than the upper section, so as to project beyond the edge of the latter, which is adapted to rest upon the inner edge of the section B. The lower section, C, is arranged below the intermediate section, B, and is a little longer than the latter.

G G designate coiled springs arranged between the webs of the sections to hold the same apart and out of contact with each other, said springs being arranged between and secured at their ends to the webs of each section.

It will be observed that the force of the springs tend to spread the sections and webs apart, and thereby gracefully support the clothing of the wearer in place.

It will be further observed that a bustle constructed in accordance with my invention is extremely light in construction, efficient and durable in use, and that the dress and garments of the wearer can be held so as to give any desired external contour.

In the modification shown in Figs. 4 and 5 I so retain the general features of the device shown in Figs. 1, 2, and 3; but in lieu of the springs D, I employ a filling of hair or other material in the sections A B C, the shape and size of the sections remaining the same. In lieu of the springs G between the webs of the sections, I employ a stout piece of textile fabric, preferably such as is known as "wigan" in the art, which is stiffened with starch or other suitable substitute, and bent and folded upon itself so as to serve as a spring, said fabric being secured or sewed at the ends to the webs of the sections, leaving the outer ends free and independent to act upon the lower outer surface of the adjoining section to hold the same apart and extended.

Each section of my improved bustle is provided at its outer edge with a series of loops spaced apart thereon and arranged intermittently with those on the adjoining section, which serve to improve the fit and the external appearance of the dress. These loops con-

sist of a piece of textile fabric bent upon itself and secured at its ends to the cloth of the sheath of the section at the seams thereof.

Modifications in the form and proportion of the parts and in details of construction herein shown and described as an embodiment of my invention can be made without departing from the principle or sacrificing the advantages thereof—as, for instance, in lieu of having a single spring between two adjoining webs, two or more springs can be employed. I would therefore have it understood that I reserve the right to make such changes as fairly fall within the scope of my invention.

15 The word "section" used in the specification refers to the padded peripheral pockets and the webs *b c d*.

What I claim as new, and desire to secure by Letters Patent of the United States, is—

20 1. In a bustle, the combination of three or more pads, each having a web, the pads being arranged one upon another and of different dimensions, with springs interposed between the webs, to the peripheries of which the pads are attached, and a waistband common to all 25 of the pads, substantially as described.

2. In a bustle, the combination of the three pads of approximately crescent shape in plan view and circular in cross-section, each pad having a waistband common to all the webs, 30 with springs interposed between and secured to the webs of the pads, as and for the purpose set forth.

3. In a bustle, the combination of the sections of graduated sizes, their webs, a waistband to which the sections and webs thereof are secured, and loops stitched to the sections and arranged intermediately with those of the adjacent section, substantially as described. 35

4. In a sectional bustle, the combination, 40 with the sections, of a series of loops secured to the sections and arranged intermediately of the loops of an adjoining section, as and for the purpose set forth.

In testimony whereof I affix my signature in 45 presence of two witnesses.

ANNA ALPLANALB.
